UNITED STATES PATENT OFFICE.

OTTO WOLTERS, OF MAGDEBURG, GERMANY.

DEVICE AND ELEMENT FOR PERFORATING BANDS OF TYPE-COMPOSING MACHINES.

Application filed October 12, 1921. Serial No. 507,394.

To all whom it may concern:

Be it known that I, OTTO WOLTERS, a citizen of the German Republic, residing at Magdeburg, Germany, have invented certain

5 new and useful Improvements in Devices and Elements for Perforating Bands of Type-Composing Machines, of which the following is a specification.

The production of perforated register 10 strips for operating automatic composing machines is effected by means of punching devices whose punches are released successively by the depression of keys of a key board connected with the same so that the 15 punches perforate the paper strip fed through the machine. The selection of the groups of punches for the individual types is effected by a system of combination-rails which is inserted between the means for 20 releasing the punches and the keys of the key board.

These arrangements possess the serious inconvenience that the control of the division of the lines and of the justifying of the lines 25 as well as the correction of the same in the register strip thus produced offers great difficulties.

Complicated and expensive devices are required for this purpose such as counting devices which indicate the progress of the 30 width of line in course of setting by typographic dots and further apparatuses which wind back the perforated registering strip and which transfer the subsequently 35 punched correcting signs to the proper place of the strip for replacing wrong groups of perforations. The correcting is further rendered difficult as the signification of the punched groups of perforation is not always 40 easily understood. It further has to be considered that the registering strip is considerably lengthened by the addition of correcting signs whilst the wrongly punched groups of perforations remain so that the 45 consumption of paper is unduly increased and the composing or casting process proper is delayed.

All these inconveniences are avoided by the invention which relates to a device for 50 releasing the punching mechanism, said device being composed of convenient elements and produced linewise in such a manner

that registering strips can be punched which are absolutely perfect and ready for use so that they do not require any subsequent 55 treatment.

The element of which the device consists is formed like the matrices of a line composing casting machine with the difference that instead of the impressions serving as 60 moulds for the casting of the characters and signs projections are substituted which serve for the direct punching of the registering strip or for releasing the punching mechanism. 65

In order that the invention may be clearly understood, I shall proceed to describe the same with reference to the several forms of construction shown by way of example on the accompanying drawings, wherein:— 70

Fig. 1 is a perspective view of an element in which the type representing projections for releasing the corresponding punches of the punching machine are arranged at one longitudinal side only. 75

Fig. 2 is a front view, and

Fig. 3 a rear view of a line composed of such elements.

Fig. 4 shows another form of the element with the projections for the releasing of the 80 punch arranged upon 2 or 3 sides.

Fig. 5 shows an element with larger projections for actuating several adjacent releasing organs arranged upon one long side of the element only. 85

Fig. 6 shows in front view an element composed of 2 superposed parts.

The element shown on Fig. 1 has upon the one edge two projections *b* which serve to release the corresponding punch when the element travels through the punching mechanism. The position of the two projections corresponds always with a determined character or sign. The element has in one of its small edges teeth *c* so that it can be distributed with the aid of a distributing beam in the manner which is known from composing machines. The reading mark *d* for the composer can be arranged in the well known manner upon the one edge of the element. 90

The element is individually constructed for each type so that the elements can be used for composing. The line which is composed of such elements can be corrected rapidly 95 100

and easily by replacing wrong elements by the correct elements, or by adding elements which have been left out, or by adding spacing elements to complete the line to the required length, whereupon the line is justified in the usual manner, the reading marks facilitating the reading of the line.

Fig. 2 shows such a line in which between the elements which represent characters or signs spacing elements are inserted. Fig. 3 shows the back of the line with the reading marks.

If this device is made to travel through the feeling levers of the punching machine the projections of the individual elements release the corresponding levers of the punching mechanism so that the corresponding perforations are punched and the perforated strip produced in this manner does neither require any correction nor revision.

The projections of the elements could be used also directly as punches.

With this object in view the elements are made to circulate in a composing-punching machine similar to the well known line-composing-casting machines to serve instead of the matrices, in such a manner that they are returned after the punching directly into the channels of a magazine to be made ready again for the composing of the next line.

In this case the device is produced by juxtaposition of the elements released from the magazine by the depression of the corresponding keys of a key board, said elements being collected in a collector which is constructed like the assembler of a composing-casting machine of known construction. The conveying of the elements for punching and for distributing is effected also in the well known manner by means of an elevator which conducts the same directly to a receiving device which is constructed like the distributing box of a composing-casting machine. From this receiver the elements are lifted singly in the well known manner upon the incline of the punching mechanism and conveyed, transversely to their longitudinal direction, to be inserted into the spindles of the distributing device.

The punching of the line and the decomposition of the composed line by distributing the single elements is preferably effected in inverse order as the composing so that the element which has been added last to the composed line, at the right hand side edge, continuing to travel in the same direction from the left to the right, gets directly upon the distribution bar, followed by the other elements of the line.

Owing to this rapid circulation of the elements the composing can be continuous as whilst one line is composed another line is used for punching and distributed so that only so many elements are always in circulation as are required to fill two lines.

This rapid circulation and the low height of the elements are of great advantage for the construction of the composing-punching machine. Such a composing-punching machine can be essentially constructed in the same manner as the matrices composing-casting machine of known type from which it differs essentially by the substitution of the punching mechanism for the casting apparatus. The magazine of such a composing-punching machine needs not be very high and it can be arranged vertically so that the releasing device for the magazine can be of very simple construction.

A particularly favorable dimensioning of the element designed to produce sign combinations of two perforations can be obtained if the projections which are designed for releasing the punching mechanism are arranged upon several sides of the element.

Fig. 4 shows such an element which is approximately of the same height and width. An element *s* has releasing projections *x*, *y*, *z* distributed over three sides, the teeth *c* for guiding the elements upon the distributing beam of the magazine and the reading mark *d* being arranged upon the fourth side. The groups of releasing projections can be arranged, under convenient utilization of the space, upon one of the three sides or upon two of the three sides. The reading mark could be provided upon one of the three sides together with the releasing projections. For the guiding of the element in the magazine there are preferably arranged guiding projections *f*, *g*, *h*, *i*, *k* which remain inoperative when the element travels through the punching mechanism and which are distributed also over three sides. The guiding projections *h* and *i* form together at the same time the angular indentation *l* with which engage the locking cones in the magazine.

If groups of perforations of more than two poles have to be punched in the paper strip, for instance groups of eight perforations of which certain perforations are to be left out according to the combinations to be produced, a favorable dimensioning of the element is possible even if the projections are arranged upon one side only.

Fig. 5 shows such an element by way of example in which the projections for releasing the feeling levers are arranged upon the one longitudinal edge of the element.

The projections *b*³ are formed by incisions *b'*, *b*² and they serve for releasing several juxtaposed feeling levers, said projections being flush with the side face of the element. The other longitudinal edge is reserved for the reading mark *d* and for projections *i* which form between them an indentation by means of which the element is held in and can be released from the magazine.

This arrangement permits to use a very

simple releasing device in the magazine for instance a ratchet wheel revolving at every depression of a key and having noses upon which the element is suspended with the upper projection *i*.

Instead of the projections for the releasing of the punching mechanism indentations could be arranged upon the elements with which the feeling levers engage.

10 Instead of projections or indentations the elements could have holes *m* designed to operate the punching mechanism if the machine is worked pneumatically. In this case the elements must be first displaced in the 15 direction of their longitudinal plane to be conveyed singly to the punching machine. The holes in the elements register them with the corresponding holes of the punching mechanism, whereby the releasing is effected.

20 For avoiding the provision of separate line measuring devices the length of the lines is directly controlled at the setting by the elements themselves which are constructed in such a manner that their thickness 25 corresponds with the width of the character or sign to be represented, either directly or in a determined relation to the width of the type. The line composed of such elements corresponds in width directly with

30 the width of the line of types which has to be represented by the same. As it is however necessary only that the thickness of the elements be in a direct proportion to the matrices which are to be composed in the 35 automatic composing machine, there could be produced also with the aid of a single set of elements registering strips for such machines which supply a united composition composed of types of different widths.

40 The element can be composed also of several part-elements in order to obtain small sized elements which can be easily transported or, in order to reduce the number of the fundamental elements, so that for instance ten elements could be used for the 45 production of hundred characters or signs in variable combinations. With such a decimal arrangement in square, the one part of the element would correspond to the longitudinal position of the key of the composing machine to be released by the registering strip and the other part would correspond to the transverse position in the key board. These elements could however not

50 have an individual reading mark for each combined sign. In this case figures would be used in such a manner that the figures from 1 to 0 of the individual part elements joining at one side serve as numerators and 55 as denominators for a fraction which characterizes the sign. The figures are preferably arranged upon the edges of the part elements which are turned towards the com-

60 poser when the elements are being used for composing.

Fig. 6 shows an element composed of two superposed parts *n*, *o* and *p*, *r*.

I claim:—

1. A device for the production of registering strips for automatic composing machines 70 consisting of a row of plate-shaped interchangeable elements composed like a line of types, each element having on its edges fixed projections which represent in combination an individual sign and which serve for releasing the punching device, and a reading mark on the fourth edge of said element.

2. A device for the production of registering strips for automatic composing machines 75 consisting of a row of plate-shaped interchangeable elements composed like a line of types, each element having on its edges fixed projections which represent in combination an individual sign and which serve for releasing the punching device, and 80 projections for guiding holding and releasing the element in the magazine arranged on three sides in groups of two at each corner so that each group of two projections serve as a guide for the escapement cones in 85 the magazine.

3. A device for the production of registering strips for automatic composing machines 90 consisting of a row of interchangeable elements composed like a line of types, each 95 element having fixed projections on the one of its longitudinal sides arranged in accordance with the grouping of the combined perforations of three or more holes to be produced in the registering strip, and each element having projections and indentations on the other longitudinal side for holding and releasing the elements in the magazine.

4. A device for the production of registering strips for automatic composing machines 100 consisting of a row of interchangeable elements composed like a line of types, each having incisions in its edges designed to receive the feeling levers of the punching mechanism.

5. A device for the production of registering strips for automatic composing machines 105 consisting of a row of interchangeable elements composed like a line of types, each element having fixed projections which represent an individual sign and which serve for releasing the punching device and said elements being of a width which corresponds 110 with the systematic width of the characters and signs to be represented by said elements.

120 In testimony whereof I affix my signature in presence of two witnesses.
